(57) **CLAIM**

The ornamental design for a pillow, as shown and described.

DESCRIPTION

FIG. 1 is a front left perspective view of the pillow showing my new design;

FIG. 2 is a front right perspective view of the pillow thereof;

FIG. 3 is a front perspective view of the pillow thereof;

FIG. 4 is a rear perspective view of the pillow thereof;

FIG. 5 is a top perspective view of the pillow thereof;

FIG. 6 is a perspective bottom view of the pillow thereof;

FIG. 7 is a front left perspective view of the pillow, with the top portion of the pillow removed, for clarity of disclosing the arched hollow through the side corners;

FIG. 8 is a front right perspective view of the pillow, with the top portion of the pillow removed, for clarity of disclosing the arched hollow through the side corners thereof;

FIG. 9 is a left side elevational view thereof;

FIG. 10 is a front perspective view, with the top portion of the pillow removed, for clarity of disclosing the arched hollow through the side corners thereof;

FIG. 11 is a right side elevational view thereof;

FIG. 12 is a rear perspective view, with the top portion of the pillow removed, for clarity of disclosing the arched hollow through the side corners thereof;

FIG. 13 is a bottom perspective view thereof; and,

FIG. 14 is a top perspective view, with the top portion of the pillow removed, for clarity of disclosing the arched hollow through the side corners thereof.
